Primary Examiner — Susan Bennett Hattan
Assistant Examiner — Leanne Was-Englehart(74) *Attorney, Agent, or Firm* — Perkins Coie LLP(57) **CLAIM**

The ornamental design for a microphone accessory, as shown and described.

DESCRIPTION

FIG. 1 is a perspective view of a microphone accessory showing my design, as viewed from the top and front.

FIG. 2 is a front elevational view thereof.

FIG. 3 is a back elevational view thereof.

FIG. 4 is a left side elevational view thereof.

FIG. 5 is a right side elevational view thereof.

FIG. 6 is a top plan view thereof; and,

FIG. 7 is a bottom plan view thereof.

The evenly spaced broken lines depict portions of the microphone accessory that form no part of the claimed design. The uneven broken lines depict the limits of the claim. The portions between the uneven broken lines form no part of the claimed design.

1 Claim, 2 Drawing Sheets(56)
